UNITED STATES PATENT OFFICE

JAMES H. RAMBO, OF FAIRFIELD, ILLINOIS, ASSIGNOR TO SEXTON MANUFACTURING COMPANY, OF FAIRFIELD, ILLINOIS, A CORPORATION OF ILLINOIS

APPAREL GARMENT

Application filed April 17, 1930. Serial No. 444,933.

This invention relates generally to apparel garments. More particularly, my invention relates to a certain new and useful improvement in combination apparel garments adapted especially for men's and boys' wear and has for its chief object briefly the provision of a unitary garment of step-in type comprising permanently connected shirt and pants portions, which may 10 be economically manufactured, which may with convenience and facility be dressed on and taken off the person, which is exceedingly comfortable in use, permitting substantially unrestrained freedom of body movements, and which is neat and pleasing in appearance.

And with the above and other objects and advantages in view, my invention resides in the novel features of form, construction, arrangement, and combination of parts hereinabove described and pointed out in the claim.

In the accompanying drawing,—

Figure 1 illustrates in front elevation a combination garment embodying my invention;

Figure 2 is a side elevational view of the garment; and

Figure 3 is a fragmental or broken rear elevational view of the garment.

Referring now more in detail and by reference characters to the drawing, which illustrates a preferred embodiment of my invention, the garment may be wholly or in part constructed of woven, knit elastic, or other suitable fabrics and unitarily includes an upper or shirt-portion A and a lower or pants-portion B permanently joined together.

The upper or shirt portion A is fashioned and designed to comfortably fit wearers of practically all chest dimensions and includes, in turn, as preferably a unit, a back section *a* and a front section, the latter being, as it may be described, a bifurcated or forked extension of the back-section, the bight *b* of such extension being preferably of arcuate configuration adapted to fit across the back at approximately the base of the neck of the wearer, and the legs *c*, *c*, of such extension being adapted to fit upon and over the shoul-

ders and down the front of the wearer, as shown.

The lower or pants portion B is also of loose fitting type and includes a waist-band *d* and depending leg-encircling members *e*, *e*, 55 each preferably of knee-length, ample fullness of material being provided, as at *f*, in the crotch of the garment. The band *d*, in the front of the garment, has preferably the configuration in plan best seen in Figure 1, 60 being widened longitudinally the garment in the nature of an abdominal support, while the leg-members *e* may be constructed of a single piece of material suitably patterned and shaped and its marginal edges stitched together in a suitable seam 1 running longitudinally and in the rear of the garment from the crotch *f* to the waist-band *d*, as best seen in Figure 3, the leg-members *e* being permanently stitched at and along their upper margin to the lower margin of the band *d* in a suitable seam 2 extending transversely of and throughout the garment, as shown.

In the front of the garment, to facilitate putting on and taking off of the garment 75 and also for the personal convenience of the wearer, the pants-portion B is suitably provided with a neatly finished placket *g* of overlapping type extending longitudinally the garment through the band *d* and leg-members *e* to adjacent the crotch *f*, as best seen in Figure 1, the pants-portion B being thereby, as I may say, divided in the front of the garment to include relatively foldable sections *x*, *y*, adapted to be releasably retained in 80 closed overlapping relation by co-operating fastening elements, such as buttons and button-holes 3, disposed, as shown, on the belt or band parts of the pants-section *x*, *y*.

For the further convenience of the wearer, 85 one of the leg-members *e* is of divided form and to such end is provided with a neatly finished placket *h* also of overlapping type running longitudinally the garment adjacent a side thereof, as best seen in Figures 2 90 and 3, so as to provide a throw-back flap, as at 4, the placket *h* being equipped with co-operating fastening elements, such as the buttons and button-holes 5, for releasably retaining the flap 4 in closed or normal position. 100

At the opposite sides of the garment, the band *d* is provided with spaced pairs of openings, 6, 6', and 7, 7', adapted to accommodate tying-tapes 8 for adjustably varying the size-dimension of the waist-band *d* and consequently the fit of the garment around the waist and abdomen to meet the convenience or requirements of the particular wearer.

- 10 The back section *a* of the shirt portion A, which is preferably of solid type for comfort, absorption of perspiration, and ample strength for withstanding the strains of body movements imposed thereupon in wear, includes at its lower margin preferably an 15 approximately oval strip *a'* of elastic knit material, the wales of which run substantially parallel with the waist-line of the garment, and which is permanently joined to the main back-section *a* by means of a suitable 20 seam 9 disposed arcuately transversely the garment, as best seen in Figure 3, the back-section at its knit strip *a'* being of a length to extend transversely the garment approximately from hip to hip or, more specifically 25 between the rear tape-openings 6', 7', and being, in turn, permanently united or stitched to the upper margin of the band *d* by means of a suitable seam 10.

At their opposite outer margins, the back 30 section *a* and its said extension-strips *c*, *c*, are arcuately cut away inwardly, as at 11, 11, from their lower end or base towards the shoulders, the extensions *c* being of reduced 35 width to comfortably fit upon and over the shoulders, as best seen in Figure 1. From the shoulders, the extensions *c* gradually increase in breadth towards the pants-section B, to the upper margin of the band *d* to which the respective upper extensions *c* are permanently 40 united at their lower end, as by suitable respective seams 12, each extension *c* at its lower end being of such breadth as to extend transversely the garment from adjacent the front tying-opening 6, 7, to the 45 placket-opening *g*, also as best seen in Figure 1.

Along their respective inner margins, the strips or extensions *c* are thus of gradual arcuate contour from the waist to the shoulders, 50 whereby the neck-opening of the shirt-portion A of the garment extends from the bight *b* forwardly and downwardly in a tapering manner to adjacent the band *d* in the front of the garment, and due to the cut-away construction and arcuate contour, as at 11, of the back-section *a* and its extensions *c* along their outer margin, the shirt-portion A of the garment is entirely open at its opposite sides, as at *i*, permitting free and unrestrained arm- 55 movements.

It will be noted that, with the exception of the securing buttons 3, fastening elements for retaining the garment upon the body are totally eliminated, the shirt portion A being held comfortably upon the body as its exten-

sions *c* are retained in overlapping relation by the fastenings 3 of the pants portion B'. The mid back-section *a'* permits of great elasticity in the center of the back, where the strain in wear predominates, such mid-section *a'* being also preferably reinforced by a double section of material 13, all attached to the upper back-section *a* and the band *d* of the pants-portion B by three rows of elastically formed stitching comprised in the respective seams 9, 10, and the shirt portion A may be further re-enforced by strips of tape 14 running from the upper margin of the waist-band *d* in the front of the garment rearwardly over the shoulders and downwardly on the back to the opposite ends of said re-inforcing section 13, as best seen in Figures 1 and 3.

The garment should be properly fitted according to the waist dimensions of the lower or pants section B, which provides for an absolutely closed crotch as generally employed in trousers or running pants, with ample provision through the front-flap and side-leg opening for the comfort and convenience of the wearer.

The waist dimension, when fitted to the wearer, is adjustable by reasons of the tying-tapes 8 to provide for any shrinkage of the fabric, and by means of such tapes the garment may be made selectively form-fitting at the waist according to the comfort and changed measurements of the wearer, and the design of the belt or band *d* fashioned from two or more thicknesses of the fabric and form-fitting being such to act as an abdominal support.

Extraordinary freedom of movement of the arms and chest is insured by the absence of the cloth therearound and the absence of arm-holes, which often restrict arm and shoulder movements.

Sufficient allowance for a large variety of trunk measurements of the garment is provided as it is designed, and the adjustment of the side ties 8, so as to make the garment form-fitting at the waist, leaves the upper portion A loose and comfortable both on tall or short wearers. Further the shirt portion A being permanently attached to the pants portion B, not only is surplus fabric around the waist and bunching of fabric around the waist, which is so uncomfortable to the wearer of two-piece garments, wholly eliminated, but also provides against the pants portion B slipping down so low on the hips as to bind and be uncomfortable to the wearer, which is the tendency with separate garments consisting of shirt and pants sections, my new garment being so constructed that the pants portion B is combined and attached to the shirt portion A and hangs down from the shoulders and not from the hips.

The garment may be inexpensively manu-

factured with minimum of cloth or fabric, may be easily fashioned, patterned, and shaped, and provides an article which, while particularly adapted for underwear, is also 5 applicable to athletic or gymnasium suits, pajamas, beach clothing, sun suits, and the like.

It is to be understood that changes in the form, construction, arrangements, and combination of the several parts of the garment 10 may be made and substituted for those herein shown and described without departing from the nature and principle of my invention.

15 Having thus described my invention, what I claim and desire to secure by Letters Patent is:

A unitary bifurcated garment including a pants-portion comprising a waist-band 20 widened longitudinally of the garment over the abdomen and depending loin and leg-encircling members, the pants-portion being permanently closed at its crotch and having an overlapping placket extending longitudinally, and centrally in the front, of the garment 25 downwardly through the widened waist-band and leg members to adjacent the closed crotch thereof, the waist-band having pairs of spaced openings upon opposite sides 30 of the garment, a shirt-portion comprising a back section having a width at its one end approximately equal to the space between, and being permanently stitched at and transversely along its one end to the waist-band 35 in the rear of the garment intermediate, said waist-band-openings, said back-section fully extending over the back and upwardly to the neck and having at its upper end a bifurcated extension the legs of which are of 40 gradually increasing width and of a length to fit over the shoulders and to extend at their broader ends to the waist-band in the front of the garment, said legs at their broader ends having a combined width greater 45 than the distance between said pairs of waist-band openings and overlapping in the longitudinal center of the garment, said legs at their said broader ends being respectively 50 permanently stitched to the waist-band intermediate the placket and said respective waist-band openings, said extension-legs being spaced throughout their outer margin from said back-section and with said back- 55 section providing at the opposite sides of the garment elongated arm-openings extending from the shoulders to said waist-band, and tapes engaging the waist-band at 60 said openings intermediate the points of attachment of said back-section and of the respective extension-legs to the waist-band for adjustably varying the size-dimensions of 65 said waist-band, and a row of co-operative fastener elements extending longitudinally 70 centrally on the garment only on the waist-

band at said placket for removably securing the garment on the body of the wearer.

In testimony whereof, I have signed my name to this specification.

JAMES H. RAMBO.
